UNITED STATES PATENT OFFICE.

CHARLES JOHNSON, OF NEW LONDON, WISCONSIN.

CUTTER-HEAD.

No. 894,888.

Specification of Letters Patent.

Patented Aug. 4, 1908.

Application filed February 13, 1908. Serial No. 415,713.

To all whom it may concern:

Be it known that I, CHARLES JOHNSON, a citizen of the United States, residing at New London, in the county of Outagamie and State of Wisconsin, have invented a new and useful Improvement in Cutter-Heads, of which the following is a specification.

My invention relates to cutter heads for surfacing lumber and consists in arranging a plurality of pairs of knives in parallel relation upon opposite sides of a cutter head shaft with the cutting edge of each pair lying along different helical lines and making the cutting action of the knives more nearly continuous than when the knives have their cutting edges parallel with the axial line of the cutter head shaft.

My improvement is shown in the accompanying drawing, in which,—

20 Figure 1 is a side elevation of the cutter head shaft without knives. Fig. 2 is a side elevation of the cutter head shaft, with knives attached to it. Fig. 3 is a plan of one of the planer, or cutting knives. Fig. 4 is an end view of the left hand end of the cutter head, in the circumferential position of that end in Figs. 1 and 2. Fig. 5 is an end view of the right hand end of the cutter head, in the position circumferentially of that end in 30 Figs. 1 and 2. Figs. 4 and 5 are upon a smaller scale than Figs. 1, 2 and 3.

Similar numerals indicate like parts in the several views.

The cutter head 1 is formed with opposite 35 knife seats in parallel relation for receiving any suitable number of pairs of knives, in the present case five pairs of seats, 2, 3, 4, 5 and 6 are shown, and they are arranged in approximately uniformly stepped helical positions around the cutter head, the seats having straight even faces adapted for having planer knives, 7, 8 and 9 bolted to them, bolt holes 10 being provided for receiving bolts 11, with a washer 11^a, between bolt head and 45 knife. The knives are all of the same form excepting the end ones 7 and 9 which are cut away on their edge for fitting the ends of the cutter head. The cutting edges 12 of the knives are curved transversely of the knives 50 on account of the angle at which they lie relative to the axial line of the cutter head with such a curve as will, when the knives are bolted in position upon the cutter head, cut a straight even surface upon the lumber 55 being planed.

It will be observed that the cutting edge of

each pair of knives is located in different helical lines circumferentially of the circle in which said edges revolve, and that there is a small distance, 13, from the last cutting of 60 one knife to the commencement of the cut in the succeeding knife, and that with the ten knives as herein shown, there will be ten separate moments of cutting and a like number of moments of nearly uniform length of 65 no cutting at each revolution of the cutter head, instead of but two of each, as in the usual two knife cutter head with the cutting edges of the knives parallel with the axial line of the cutter head, the cutting action of 70 the knives being thereby distributed more evenly over the entire circle of revolution of the cutting edge in the helical, than in the parallel arrangement of the cutting edge. The cutting action of the knives when ar- 75 ranged in helical lines is a drawing cut, that is, it is not a square cut across the article planed.

The distance from the last cutting of the knives 7 to the commencement of the cutting 80 of the knife 9, may be approximately the same as the distance between 7 and 8, 8 and 8 or 8 and 9.

The knives upon one side, say the upper side in Fig. 2, are intended to cut, (aside 85 from the short spaces 13 between them), substantially one half of the circle in which their cutting edges revolve, or in longer cutter heads than here shown, they may be continued in the same helical line, (of more or 90 less angle with the axial line, than here shown,) and complete the circle if desired, the object being to distribute the cutting action of the knives evenly entirely around the cutter head, whether it be longer or shorter 95 than the one here shown, the angle of the knife seats transversely of the cutter head and the width of the knives and their seats being made to correspond with the length of the cutter head. 14, indicates the journals 100 of the cutter head, 15, chip breakers.

Having described my invention, what I claim and desire to secure by Letters Patent, is,—

1. A cutter head, a plurality of seats in 105 parallel relation upon opposite sides of the cutter head arranged in pairs, each seat having a plain even surface for receiving and having secured thereon a cutting knife, the seats of each pair being adapted for having the 110 cutting edges of their knives arranged helically around the axial line of the cutter head, each

pair of seats being arranged in helical lines different circumferentially of the cutter head from the helical lines of an adjoining pair of seats, substantially as described.

- 5 2. A cutter head, a plurality of seats in parallel relation upon opposite sides of the cutter head arranged in pairs, each seat having a plain even surface for receiving a cutting knife, a knife bolted upon each seat, the
10 cutting edge of each knife being curved transversely of the knife upon such a curve that when the head is revolved the knives will cut a flat even surface upon the article

being planed, their cutting edges being arranged helically around the axial line of the 15 cutter head, said helical lines of each pair of knives being arranged in a different position around the cutter head from the helical lines of an adjoining pair, which helical lines are spaced apart around the cutter head at 20 nearly equal distances, substantially as set forth.

CHARLES JOHNSON.
